United States Patent Office

Des. 178,800
Patented Sept. 18, 1956

178,800

LICENSE CARD HOLDER

Norman J. McKinnon, Beacon Falls, Conn.
Application May 4, 1955, Serial No. 35,804

Term of patent 14 years

(Cl. D87—3)

Fig. 1

Fig. 2

Fig. 3

Fig. 1 is a plan view of the license card holder showing my new design.

Fig. 2 is an end view of the same.

Fig. 3 is a longitudinal, sectional view of the same taken along the line 3—3 of Fig. 1.

I claim:

The ornamental design for a license card holder, substantially as shown.
